CUP HANDLE

Gustaf Sigfrid Hanson, Montclair, N. J.

Application August 11, 1934, Serial No. 739,492

3 Claims. (Cl. 229—52A)

This invention relates to paper cups and more particularly to a handle therefor.

An object of the present invention is to provide a handle which may be so associated with a paper cup as to fold therewith to permit vending of the cup and handle as a unitary structure.

A further object of the invention is to provide a handle of destructible material which can be readily and easily applied to the paper cup.

10 The invention, together with its objects and advantages, will be best understood from a study of the following description, taken in connection with the accompanying drawing, wherein:

Figure 1 is an elevational view of a paper cup 15 having the handle associated therewith, coacting parts of the handle being separated.

Figure 2 is a sectional view taken substantially on the line 2—2 of Figure 1.

20 Figure 3 is a view similar to Figure 1 with the cooperating portions of the handle inter-engaged.

Figure 4 is a sectional view taken substantially on the line 4—4 of Figure 3.

25 Referring to the drawing by reference numerals, it will be seen that 5 indicates generally a paper cup of known and conventional construction. The improved handle for the cup is indicated by the reference numeral 6 and is formed from thin cardboard or other suitable and de-structible material. The handle 6, as will be

30 noted, is formed from a single blank of the desired and selected material cut, shaped, and dimensioned to provide an attaching portion 7 that is adhesively secured to the wall of the cup as at 8, and foldable flap or handle sections 9 and 10 that

35 are adapted, when the cup is to be used, to be folded back on the attaching portion 7 and then extended substantially radially to the cup as shown in Figures 3 and 4. One of the folds or handle sections, for example, the fold or handle

40 section 9 at its free end is reversely folded upon itself to provide a fold 11 which, at its upper and lower edges, is permanently united with the section 9 as at 12 by adhesive or in any other suitable manner. The fold 11 thus united with the section 9 forms a pocket to receive a tongue 13 suitably formed on the free end of the fold or section 10 by cutting away the corners of the fold or section 10 at the free end thereof.

When the sections 9 and 10 are folded back to provide the handle, the tongue 13 is inserted in the pocket 14 formed by the fold 11 thus connecting the free ends of the sections 9 and 10 in a manner shown in Figure 4 for maintaining said sections substantially radial to the cup to thereby provide a suitable handle for the cup.

When the cup is packed for vending purposes, the handle sections 9 and 10 are disposed about the cup, concentric thereto and in a manner clearly shown in Figures 1 and 2. With the sections 9 and 10 thus disposed about the cup it will be apparent that a plurality of such cups may be telescoped for vending from a suitable machine, and for packing and shipping purposes.

5 What is claimed is:

1. A handle for cups of destructible material comprising an attaching part adapted to be secured to the wall of the cup, and handle sections united with the attaching part and foldable relative thereto to extend in a direction radial to the cup, and inter-engaging means on the free ends of the sections for detachably connecting said ends of the sections in a manner to hold the same in a predetermined operative position 25 relative to the cup.

2. In combination, a destructible cup, a de-structible handle for the cup comprising an attaching part united to the wall of the cup, and handle-forming sections foldable relative to the 30 attaching part into either a position concentric to the cup or to a position substantially radial to the cup, optionally, and inter-engaging means on the free ends of the sections for detachably connecting said ends together to hold the sections in handle-forming position.

3. As a new article of manufacture, a paper cup having handle sections united with the wall thereof and foldable relative to the wall towards one another, one of said handle sections having a free end provided with a pocket, and the other of said handle sections having a free end provided with a tongue adapted to be inserted into the pocket for holding said sections in a predeter- 45 mined handle-constituting position relative to the cup.

GUSTAF SIGFRID HANSON.
